UNITED STATES PATENT OFFICE.

MARSHALL BIDWELL INGERSOLL, OF REGINA, MANITOBA, CANADA.

FIRE-ESCAPE.

SPECIFICATION forming part of Letters Patent No. 320,474, dated June 23, 1885.

Application filed May 12, 1885. (No model.) Patented in Canada April 7, 1884, No. 35,731.

To all whom it may concern:

Be it known that I, MARSHALL BIDWELL INGERSOLL, lumber-dealer, of Regina, in the Province of Manitoba, Canada, have invented 5 certain new and useful Improvements in Fire-Escapes, of which the following is a specification.

My invention relates to that class of fire-escapes commonly known as "escape-ladders;" and it has for its object to simplify 10 and cheapen the construction, while at the same time rendering the apparatus strong and safe.

In the drawings, Figure 1 is a perspective 15 view showing my apparatus in use. Fig. 2 is an inside face view of a window-casing, showing my improved escape applied thereto; and Fig. 3 is a detail view.

This invention consists in a novel manner 20 of mounting the reel upon which the ladder is wound.

A indicates a window-casing, at each side of which is a bracket, B, secured in position by screws or bolts, as shown in Fig. 2. The 25 form or shape of this bracket may be varied to give a more or less ornamental appearance, and it is provided with a vertical hole or perforation, a, as shown in Fig. 3.

C indicates a box or block provided with 30 a depending arm or stud, b, to fit the hole or opening a in the bracket B, and with an enlarged head having a horizontal hole or opening, c, as indicated in Fig. 3. This head or enlargement prevents the block from dropping down through the hole or opening a too 35 far, and it forms a bearing for the shaft D of the reel.

Shaft D extends across the window from 40 one side to the other, and its ends pass through and revolve in the holes or openings c in the blocks C, the shaft being extended at one end beyond the side of the block C, and provided with a crank or handle, d, by which 45 to turn it.

The opposite end of the shaft D is provided with a nut, e, by which it is prevented from escaping from its box or bearing C.

The shaft D is furnished with a balance-wheel, f, and with disks g, as shown in 50 Fig. 2.

The wheel f may be used to wind or un-

wind the ladder, instead of using the crank-handle d, or may be used to control the descent of the ladder.

The disks g are not essential, but they serve 55 to keep the ladder in place, and cause it to wind and unwind more evenly than when they are not used.

The shaft D is provided with holes h, through which the ends of the ladder are 60 passed in securing the ladder to the shaft; but it is apparent that any equivalent manner of securing the ladder to the shaft may, obviously, be used.

E indicates the ladder, which may be made 65 of wire, rope, or any other material that will readily wind around the shaft D, and to the end of said ladder I attach a weight, F, which, when the ladder is extended, keeps the ladder taut, and prevents swaying.

When the ladder is not in use and is wound 70 up, the weight rests upon the window-sill or upon the floor, out of reach of persons upon the ground; and if for any reason it should be desired to remove the escape from the window, the shaft with the ladder wound thereon is lifted with its boxes or blocks C out of the stationary brackets or supports B.

The stems b of the blocks C are preferably 75 made cylindrical, so as to allow them to adjust and align themselves, and prevent any binding of the shaft in its journals.

The escape may be adapted to windows of varying widths, the shaft D sliding through the boxes or bearings C, and retained in place 85 by the nut e and set-screw or collar i. (Shown in Fig. 2.)

Having thus described my invention, I claim—

1. In a fire-escape, the combination, with 90 a window-casing and brackets secured thereto, of a shaft, a ladder wound upon said shaft, and boxes supporting the shaft and loosely mounted in the brackets, as set forth.

2. In combination with window-frame A, 95 brackets B, secured to the inner faces thereof, blocks C, mounted in said brackets, shaft D, journaled in said blocks, and ladder E, wound upon said shaft, and provided with weight F, all constructed and arranged to operate as set forth.

3. In a fire-escape, the combination, with

a window-casing, of brackets B, secured thereto, and provided with opening a, and blocks C, provided with stem b and holes c, and adapted to support the ladder shaft or reel, as set forth.

5 4. In combination with casing A, brackets B, provided with hole a, blocks C, provided

with stems b, shaft D, journaled in the blocks C, and provided with ladder E, and hand-wheel f, as and for the purpose set forth.
